Howard P. King.

INVENTOR:

Walter W. Giveans,
Russell M. Everett,
ATTORNEY.

UNITED STATES PATENT OFFICE.

WALTER W. GIVEANS, OF NEWARK, NEW JERSEY.

DESIGN FOR A PICTURE-FRAME.

48,545.

Specification for Design.

Patented Feb. 15, 1916.

Application filed October 12, 1915. Serial No. 55,587. Term of patent 14 years.

To all whom it may concern:

Be it known that I, WALTER W. GIVEANS, a citizen of the United States, residing at Newark, in the county of Essex and State of New Jersey, have invented a new, original, and ornamental Design for Picture-Frames, of which the following is a specification, reference being had to the accompanying drawing, forming part thereof.

The figure is a face view of a picture frame embodying my invention.

I claim:

The ornamental design for a picture frame, as shown.

WALTER W. GIVEANS.
